UNITED STATES PATENT OFFICE.

JAMES R. FEELEY, OF PROVIDENCE, RHODE ISLAND.

DESIGN FOR A LOCKET.

44,524.

Specification for Design.

Patented Aug. 19, 1913.

Application filed February 20, 1913. Serial No. 749,740. Term of patent 7 years.

To all whom it may concern:

Be it known that I, JAMES R. FEELEY, a citizen of the United States, residing at Providence, in the county of Providence and State of Rhode Island, have invented a new, original, and ornamental Design for Lockets, reference being had to the accompanying drawings, in which the figure is a view of the locket in open position.

I claim—

The ornamental design for a locket as shown.

JAMES R. FEELEY.

Witnesses:

ADA E. HAGERTY,
J. A. MILLER.
